(57) **CLAIM**

The ornamental design for a specimen analysis apparatus as shown and described.

DESCRIPTION

FIG. 1 is a front, top, right side perspective view of a specimen analysis apparatus showing our new design; FIG. 2 is a front, bottom, right side perspective view thereof; FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings are for the purpose of illustrating portions of the specimen analysis apparatus that form no part of the claimed design.
